UNITED STATES PATENT OFFICE.

HENRY RICHARDSON, OF CHICAGO, ILLINOIS.

WIRE FABRIC.

1,248,553.

Specification of Letters Patent.

Patented Dec. 4, 1917.

Application filed February 19, 1914. Serial No. 819,645.

To all whom it may concern:

Be it known that I, HENRY RICHARDSON, a subject of the King of Great Britain, residing at Chicago, in the county of Cook 5 and State of Illinois, have invented certain new and useful Improvements in Wire Fabrics, of which the following is a specification.

This invention relates to wire fabrics, and has reference more particularly to wire 10 fabrics of the kind at present extensively used to form the bottoms of beds, couches, and like articles of furniture.

One type of bed and couch fabric now largely employed is characterized structurally by the presence of parallel longitudinal strands composed of interhooked bent wire units or links connected transversely at intervals by wire cross-links. The interhooking of the links forming the longitudinal strands 15 20 in this type of fabric creates a weakness at these points of connection, owing to the liability of the hooks to pull or straighten out under tension. This same weakness also inheres in fabrics wherein the end portions 25 of the wire forming each link are connected merely by interengaging hooks on said ends or by a hook on one end engaging a loop on the other end, since in all such cases there is present in the link at or intermediate its 30 ends one or more hooks having a free or unsecured bent portion in the direct line of longitudinal strain, the strength of which to resist tensional strains is far below the breaking point of the wire itself.

35 The general object of my present invention is to provide a new and improved link wire fabric structure of a type heretofore originated by me and which is especially characterized by the fact that it employs 40 two-ply links each formed from a single piece of wire in each longitudinal strand and may be made of a considerably lighter gage of wire than was theretofore known in fabrics of that character. This object I accomplish 45 by a novel structure of link that entirely obviates the presence anywhere in a fabric of the type described of unsecured ends of loops or hooks in a line of longitudinal strain. My present invention is capable of 50 embodiment both in fabrics of the type employing an integral cross-arm, and in the type employing a separate cross-link, to form the connection between adjacent longitudinal strands.

55 In the accompanying drawings I have

illustrated my invention both in the integral cross-arm type of fabric and in the separate cross-link type of fabric; and, referring thereto—

Figure 1 is a fragmentary top plan view 60 of a wire fabric for bed and couch bottoms, illustrating my invention as embodied in a wire fabric of the integral cross-arm type. Fig. 2 is a perspective detail from the upper side of a portion thereof. Fig. 3 is an enlarged perspective detail from the under side of a portion of one of the links thereof. Fig. 4 is a cross-sectional detail, enlarged, on the line 4—4 of Fig. 1. Fig. 5 is a fragmentary top plan view of a wire fabric for bed and 70 couch bottoms illustrating my invention as embodied in a wire fabric of the separate cross-link type. Fig. 6 is a perspective detail from the upper side of a portion of Fig. 5. Fig. 7 is an enlarged perspective detail 75 from the under side of a portion of one of the longitudinal links of Fig. 5. Fig. 8 is a fragmentary top plan view of a somewhat simplified variation of the fabrics of Figs. 1 to 4 inclusive. Fig. 9 is a bottom plan 80 view of a portion of one of the edge-strand links of Fig. 8. Fig. 10 is a fragmentary top plan view of the fabric of Figs. 8 and 9 as modified to form a separate cross-link fabric. Fig. 11 is a bottom plan view of a portion of one of the longitudinal links of Fig. 10. Fig. 12 is a fragmentary top plan 85 view of another variation of the fabric of Figs. 1 to 4 inclusive. Fig. 13 is a bottom plan view of a portion of one of the edge- 90 strand links of Fig. 12. Fig. 14 is a fragmentary top plan view of the fabric of Figs. 12 and 13 as modified to form a separate cross-link fabric. Fig. 15 is a bottom plan view of a portion of one of the longitudinal 95 links of Fig. 14.

The novel fabric of my invention, in all of the forms illustrated, includes a plurality of links or units each composed of a single length of wire that is bent to provide the 100 characteristic features, common to all the forms shown, of a two-ply body member having closed ends, with the end portions of the wire interlockingly engaged with each other between the ends of the two-ply 105 body member, one of said end portions being clenched to the link, and the other of said end portions being bent to form a laterally projecting loop or eye on one side of the body member, and being thence extended 110

across said body member and forming an element of a cross-connection between the two-ply body members of laterally adjacent links of the fabric. This cross-connection element may take the form either of a cross-arm engaging a lateral loop or eye of a laterally adjacent link, or it may take the form of a lateral loop or eye on the opposite side of the body member from said first-named lateral loop or eye that is clenched to the link and adapted to be engaged by a separate cross-link.

In all the embodiments of the invention herein presented, the wire of which each main longitudinal link is composed is bent in such a manner as to provide a two-ply body or tension member 10 the limbs of which are joined at one end preferably by means of a simple U-bend or loop 11, and are preferably joined at the other end by means of a two-ply loop 12, the sides of which two-ply loop are integrally joined across the body member, as clearly shown in the perspective views, Figs. 2 and 6. Furthermore, in all of the forms illustrated the end portions of the wire are interlockingly engaged with each other between the ends of the link and in the line of one limb of the body member, one end portion, from said point of interlocking engagement, being thence looped around and clenched to an element of the link, and the other end portion, from said point of interlocking engagement, being bent to form a loop or eye on one side of the body member and an element of a cross-connection on the opposite side of said body member.

Referring first to the embodiment shown in Figs. 1 to 4 inclusive, 13 indicates the point at which the two end portions of the wire of each link are interlockingly engaged with each other by extending across each other at their angular bends or junctions with one limb of the body member from which they spring. The longer end portion of the wire extends, from the intersection 13, laterally of one side of the body member in the form of a loop or eye 17, and thence across and laterally of the opposite side of the body member in the form of an integral cross-arm 18, which latter terminates at its outer end in a loop 19 that extends through the eye 17 of a laterally adjacent link, and has its free end clenched to the body of the cross-arm 18, as shown at 20. The shorter end portion of the wire extends, from the intersection 13, beneath the base of the lateral loop 17, as shown at 14 (Fig. 3), thence up and across the upper side of the body member, as shown at 15, and thence beneath the body member, as shown at 16, whereby said short end portion is not only securely clenched to the body member, but also serves to tie together the two limbs of the body member just beneath the cross-arm

18. On one longitudinal edge of the fabric (the upper as shown in Fig. 1) the cross-arm 18 is not required, and the wire forming the same is cut off a slight distance beyond the side of the body member and is bent and clenched beneath the latter alongside the clenched end 16, as shown at 21 in Fig. 4.

The form of the invention illustrated in Figs. 5 to 7 inclusive differs from that of Figs. 1 to 4 inclusive only in that the longer end portion of the wire, instead of forming an integral cross-arm such as 18, is bent to create another lateral loop or eye 22 opposite and corresponding functionally with the loop or eye 17, the extreme end portion of the wire being carried back across and clenched to the body member as shown at 23 in Fig. 7. The lateral loops 17' and 22 of laterally adjacent links are, in this case, flexibly connected by a cross-link 24, both ends of which are provided with loops 19' the free ends of which are clenched to the body portion of the cross-link at 20'.

Figs. 8 and 9 illustrate a somewhat simplified variation of the fabric of Figs. 1 to 4 inclusive. In this case, the longer end portion of the wire is treated the same as in the fabric of Figs. 1 to 4 inclusive, being extended from the point of intersection 13' to form, first, the lateral loop or eye 17^a, and, thence, the integral cross-arm 18' extending across the body member and projecting on the opposite side of the latter. The short end portion of the wire in this case starts from the upper side of the intersection 13', is thence carried across the upper side of the lateral loop 17^a, as shown at 25, and is then clenched beneath the lateral loop or eye 17^a as shown at 26 in Fig. 9. This construction employs slightly less wire to form the link than the construction of Figs. 1 to 4 inclusive, and affords no less tensile strength in the two-ply body or tension member, but, of course, omits the feature of tying together the two limbs of the body member beneath the cross-arm. In the formation of the upper edge strand, where the cross-arm is omitted, the wire is cut off and clenched beneath the outer side of the body member as shown at 27 in Fig. 9.

Figs. 10 and 11 illustrate a modification of the fabric of Figs. 8 and 9 to adapt the same to the separate cross-link type. All that is necessary for this is to bend or loop back the wire that is used to form the cross-arm 18' so as to produce the lateral loop or eye 22', the free end of which is clenched beneath the body member as shown at 23'; the construction in this respect following that of Figs. 5, 6 and 7.

Figs. 12 and 13 illustrate a further variation in the general forms and structures of fabric shown in Figs. 1 to 4 inclusive and Figs. 8 and 9. In this case, the longer end

portion of the wire is disposed of as in the forms and structures last referred to, but the shorter end portion of the wire, from the point of intersection 13^a is carried first 5 across the base of the lateral loop or eye 17^b, as shown at 25', thence beneath the two-ply body member, as shown at 28 (Fig. 13), and its free extremity is curled around and clenched to the cross-arm 18^a, as shown at 10 29 (Fig. 13).

Figs. 14 and 15 show a modification of the fabric of Figs. 12 and 13 to adapt the same to the separate cross-link type; this modification being the same as that already 15 described in connection with Figs. 5, 6 and 7, and Figs. 10 and 11, and consisting of bending or looping back the longer end portion of the wire, after it has crossed the two-ply body member, to form the lateral 20 loop or eye 22^a and clenching the free end thereof beneath the body member, as shown at 23^a in Fig. 15.

It will be evident that in all of the forms of the invention illustrated, the end portions of the wires forming the links are securely locked against pulling out under strain since each of their extremities is securely clenched to some part or element of the link. It will be observed that in the 30 present case I have shown this principle as embodied in constructions wherein the free end portion of the wire is clenched to the body or tension member of the link, to the laterally projecting loop or eye, and to the 35 integral cross-arm. All of these constructions afford good results in practice, and a selection between them will, naturally, be determined largely by convenience and economy of manufacture; it being immaterial, 40 so far as the invention broadly is concerned, whether the clenching of the free end of the wire is done to the body member, to the cross-arm, or to the lateral eye. The form illustrated in Figs. 8 to 11 inclusive, 45 represent the simplest and most practical forms from the standpoint of ease and economy of manufacture.

I claim—

1. A wire link fabric including a plurality of links or units, each composed of a single length of wire bent to form a two-ply body member, with the end portions of the wire interlockingly engaged with each other between the ends of the body member, 55 one of said end portions being extended beyond said interlocking engagement crosswise over and beneath the body member and clenched to the latter, and the other end portion being bent to form a laterally projecting loop or eye on one side of the body member and thence extended across the latter and forming an element of a cross connection between the body members of laterally adjacent links or units of the fabric; 60 said links or units being flexibly connected 65

end to end to form longitudinal strands, and said longitudinal strands being flexibly connected laterally throughout the fabric.

2. A wire link fabric including a plurality of links or units each composed of a single length of wire bent to form a two-ply body member, with the end portions of the wire interlockingly engaged with each other between the ends of the body member, one of said end portions being bent to form a laterally projecting loop or eye on one side of the body member and thence extended across the latter and forming an element of a cross connection between the body members of laterally adjacent links or units of the fabric, and the other end portion embracing both sides of said loop or eye and thence extending crosswise over and beneath the body member and clenched to the latter; said links or units being flexibly connected end to end to form longitudinal strands, and said longitudinal strands being flexibly connected laterally throughout the fabric. 75 80 85

3. A wire link fabric including a plurality of links or units each composed of a single length of wire bent to form a two-ply body member, with the end portions of the wire interlockingly engaged with each other between the ends of the body member, one of said end portions being bent to form a laterally projecting loop or eye on one side of the body member and thence extended across the latter and forming an element of a cross-connection between the body members of laterally adjacent links or units of the fabric, and the other of said end portions embracing both sides of said laterally projecting loop or eye beyond the point of interlocking engagement; said links or units 90 95 100 being flexibly connected end to end to form longitudinal strands, and said longitudinal strands being flexibly connected laterally throughout the fabric. 105

4. As an article of manufacture, a wire fabric link consisting of a single length of wire bent to form a two-ply body member, with the end portions of the wire interlockingly engaged with each other between the ends of the body member, one of said end portions being extended beyond said interlocking engagement crosswise over and beneath the body member and clenched to the latter, and the other end portion being bent to form a laterally projecting loop or eye on one side of the body member and thence extended across the latter and forming an element of a cross connection between the body members of laterally adjacent links or units of the fabric. 110 115 120 125

5. As an article of manufacture, a wire fabric link consisting of a single length of wire bent to form a two-ply body member, with the end portions of the wire interlockingly engaged with each other between the 130

2
ends of the body member, one of said end portions being bent to form a laterally projecting loop or eye on one side of the body member and thence extended across the latter and forming an element of a cross connection between the body members of laterally adjacent links or units of the fabric, and the other end portion embracing both sides of said loop or eye and thence extending crosswise over and beneath the body member and clenched to the latter.

16. As an article of manufacture, a wire fabric link consisting of a single length of wire bent to form a two-ply body member, with the end portions of the wire interlock-

ingly engaged with each other between the ends of the body member, one of said end portions being bent to form a laterally projecting loop or eye on one side of the body member and thence extended across the latter and forming an element of a cross-connection between the body members of laterally-adjacent links or units, and the other of said end portions embracing both sides of said laterally projecting loop or eye beyond the point of interlocking engagement. 20 25
